UNITED STATES PATENT OFFICE.

LOUIS M. GRAUBARTH, OF NEW YORK, N. Y.

COLLAR-SUPPORT.

1,083,826.

Specification of Letters Patent.

Patented Jan. 6, 1914.

Application filed January 31, 1913. Serial No. 745,425.

To all whom it may concern:

Be it known that I, LOUIS M. GRAUBARTH, a citizen of the United States, and a resident of the city of New York, borough of Manhattan, in the county and State of New York, have invented a new and Improved Collar-Support; of which the following is a full, clear, and exact description.

The invention relates to negligée shirts having soft turned-down collars, and its object is to provide a new and improved support or stiffener arranged for convenient attachment to the collar with a view to prevent the turned-down front portions of the collar from wrinkling up, and to hold the same in properly stretched positions, thus insuring at all times a neat appearance of the collar.

In order to accomplish the desired result, use is made of a fastening member adapted to be placed intermediate the neckband and the turned-down portions of the collar, the upper edge of the fastening member abutting against or being in close proximity to the joint of the neckband with the turned-down portions, the said fastening member being provided with buttons disposed at opposite sides of the median line of the stiffening member to engage the usual buttonholes in the turned-down front portions of the collar.

A practical embodiment of the invention is represented in the accompanying drawings forming a part of this specification, in which similar characters of reference indicate corresponding parts in all the views.

Figure 1 is a perspective view of a shirt having a turned-down collar provided with the support; Fig. 2 is a perspective view of the support; Fig. 3 is a face view of the same with one of the buttons shown in section; and Fig. 4 is an enlarged transverse section of the same on the line 4-4 of Fig. 3.

The soft collar support consists essentially of a stiffening member A, preferably of horseshoe shape, and adapted to be placed intermediate the neckband B' and the turned-down front portions B² of a soft collar B, as plainly indicated in Fig. 1. The stiffening member A is preferably made of sheet metal in the form of a horseshoe, provided at the upper ends with sidewise-extending flanges C adapted to abut against the joint or junction of the neckband B' with the turned-down front portions B² of

the collar B. The stiffening member A is provided at the bottom with a slot or recess D adapted to be seated on the shank of a collar button E so as to support the stiffening member A and assist in holding the same in position on the collar B, as above described and shown in Fig. 1. Buttons F are held on the stiffening member A on opposite sides of the median line of the said stiffening member, and the said buttons F are adapted to engage the usual buttonholes B³ formed in the turned-down front portions B² of the collar B, as shown in Fig. 1. As the positions of the buttonholes B³ vary, it is desirable to permit of changing the positions of the buttons F on the stiffening member A to correspond to the buttonholes B³, and for this purpose the buttons F are adjustably mounted on the stiffening member A.

As shown in the drawings, the stiffening member A is provided with slots G through which extends the shank extensions F' of the buttons F, and on the shank extensions F' are held front and rear washers H and H' engaging the front and rear faces of the stiffening member A, as plainly indicated in Fig. 4. Each of the slots G is provided with a number of seats spaced apart and extending in different directions, any one of the seats being adapted to be engaged by the shank extension F' of the corresponding button F.

It will be noticed by reference to Fig. 3 that each of the slots G with its seats permits of adjusting the button up or down or sideways to properly locate the buttons on the stiffening member A relative to the positions of the buttonholes B³ on the turned-down front portions B² of the collar B.

It will be noticed that when the support is in position on the collar, the turned-down front portions B² of the collar are held stretched in an up and down direction owing to the buttons F engaging the buttonholes B³ and the arms C abutting against the joint of the neckband B' with the turned-down front portions B² of the collar. It will further be noticed that the collar support does not interfere in the least with the necktie, and the support prevents the turned-down front portions of the collar from wrinkling up, so that a neat appearance of the collar is had.

Having thus described my invention, I

claim as new and desire to secure by Letters Patent:

1. A collar support, comprising a stiffening member adapted to be placed between the neckband and the turned-down front portions of the collar, the said stiffening member having upwardly extending spaced portions terminating in laterally extending arms, the upper edges of the said arms abutting against the joint of the said neckband and turned-down portions, and buttons held adjustable sidewise and up and down on the said stiffening member and disposed at opposite sides of the median line of the said stiffening member, the said buttons being adapted to engage buttonholes in the front turned-down portions of the collar.
2. A collar support, comprising a stiffening member adapted to be placed between the neckband and the turned-down front portions of the collar, the upper edge of the stiffening member abutting against the joint of the said neckband and turned-down portions, the said stiffening member being provided at the lower side portions with slots, and buttons held adjustable in the said slots and adapted to engage buttonholes in the front turned-down portions of the collar.
3. A collar support, comprising an approximately horseshoe-shaped stiffening member terminating at its upper ends with arms extending sidewise in opposite direc-

tions, the lower side portions of the member being provided with slots having a plurality of seats, and buttons one for each slot and adapted to engage buttonholes in the turned-down front portions of the collar, each button having a shank extension engaging the slot and adapted to be seated in any one of the seats, and washers held on the shank extension and engaging the front and rear faces of the stiffening member.

4. A collar support, comprising a stiffener made of sheet material and having a bottom member and upwardly extending spaced side members, the bottom member being provided in its lower edge with a collar button slot arranged in the median line of the stiffener and adapted to engage the shank of the collar button, the upwardly extending spaced members terminating at their upper ends in arms extending sidewise in opposite directions, and buttons on the lower part of said stiffener and disposed at opposite sides of the median line of the stiffener, and the said button hole slot.

In testimony whereof I have signed my name to this specification in the presence of two subscribing witnesses.

LOUIS M. GRAUBARTH.
